UNITED STATES PATENT OFFICE

FRANCES R. BROWN, OF NEW YORK, N. Y., ASSIGNOR TO I. B. KLEINERT RUBBER COMPANY, OF NEW YORK, N. Y.

DESIGN FOR A HOT-WATER BOTTLE OR ARTICLE OF SIMILAR NATURE

Application filed April 23, 1930. Serial No. 35,362. Term of patent 7 years.

To all whom it may concern:

Be it known that I, FRANCES R. BROWN, a citizen of the United States, residing in New York, in the county of New York and State of New York, have invented a new, original, and ornamental Design for a Hot-Water Bottle or Article of Similar Nature, of which the following is a specification, reference being had to the accompanying drawing, forming a part thereof.

Fig. 2 is a side elevational view thereof.

I claim:

The ornamental design for a hot-water bottle, or article of similar nature, as shown.

In testimony whereof I affix my signature.

FRANCES R. BROWN.
